UNITED STATES PATENT OFFICE.

FOLGER ADAM, OF JOLIET, ILLINOIS.

FENCE MACHINE AND THE LIKE.

Application filed October 11, 1926. Serial No. 140,742.

The present invention has to do with improvements in fence machines. It has reference particularly to improvements in machines for manufacturing what is known as 5 "slat" fence, but it will be understood that the features of the invention are not limited to use in machines for manufacturing this particular kind of fence except as I may limit myself in the claims. Nevertheless, in view 10 of the fact that the features of the invention are especially well adapted for manufacturing picket or slat fence, I have illustrated and will describe the invention for this particular class of service.

15 The main feature of the invention is to provide means for taking up the fencing at a uniform rate so as to allow the weaving or fence manufacturing process to continue in a substantially uninterrupted manner over a 20 long period of time. The take-up mechanism is so arranged that during intervals when the reels upon which the completed fence is wound are being changed the fencing being woven will be stored up and delivered to the 25 next reel after the same is in place and in operation.

This will make it unnecessary to shut down the weaving operation during intervals when the reels are being changed or adjusted, thus 30 greatly increasing the daily capacity of the machine as a whole, and also reducing the labor and other costs, such as overhead, etc.

Another feature of the invention relates to the provision for taking up the fencing in 35 the aforesaid manner, whether the machine be of the continuous or intermittent type. In other words, the features of the present invention are not limited either to continuous feed or intermittent feed machines, but may 40 be used to advantage in both kinds of machines.

Other objects and uses of the invention will appear from a detailed description of the same, which consists in the features of construction and combinations of parts herein- 45 after described and claimed.

In the drawings,—

Fig. 1 shows a plan view of a fence machine of the intermittent type having applied thereto a take-up mechanism embodying the features of the present invention; 50

Fig. 2 shows a fragmentary side elevation corresponding to the machine of Fig. 1;

Fig. 3 shows a perspective view of the 55 winding sticks and one of the end blocks in

which they are mounted, and shows the manner in which the slat fencing is engaged with the sticks in order to cause proper reeling;

Fig. 4 shows a view similar to that of Fig. 2 with the exception that it illustrates the 60 features of the invention as applied to a machine of the continuous feed type; and

Fig. 5 shows a fragmentary elevation of a portion of the machine illustrated in Fig. 1, and illustrates a slip clutch such as is used 65 for driving the winding reel.

Referring first to Fig. 1, the machine therein illustrated includes a number of coiling heads 6, through which the strand wires 7 are introduced in pairs. The individual slats 8 are originally fed from the stack or pile 9 to suitable placing rolls or the like 10, whereby they are projected between the pairs of strand wires during intervals when the coiling heads 6 are idle. After each slat has been 70 projected into place between the strand wires the completed fencing is advanced in the direction of the arrow shown in Fig. 1, and at proper intervals the coiling heads 6 are rotated so as to twist the pairs of strand wires, 75 and thus complete the manufacturing of the fence.

The completed fencing is taken up on a suitable winding roll or reel 11, the same being driven in suitable manner. As the 80 amount of fencing on this reel increases, the diameter of the roll increases, so that the rate of draw off must vary, and accordingly it is very customary to use a slip drive of some kind so as to allow the rate of rotation of the 85 reel 11 to accommodate itself to the changing conditions.

Usually the fence is reeled on a pair of bars 12 and 13 (see Fig. 3). The ends of these bars are loosely mounted in end blocks, such 90 as 14, in Fig. 3, said end blocks being provided with suitable sockets 15 to accommodate the ends of the bars. The fresh end of fencing 16 is introduced between the bars 12 and 13, and as said bars are rotated together by rotation of the end hubs 14, the fencing is 95 reeled up, as shown in Fig. 2. After the desired amount of fencing has been reeled, one of the end blocks 14 is removed, and the bars 12 and 13 may then be slipped away from 100 both end blocks. These bars may then be drawn out from the roll of fencing, and the bars may then be replaced between the end blocks, and the operation repeated.

Heretofore, the process of removing the 110

reeled fencing and commencing on another reel has necessarily been attended with a temporary shut down of the operation of the machine as a whole. This is because it has heretofore been customary to deliver the fencing directly to the reel. According to my present invention, I interpose between the weaving elements proper and the reeling mechanism a suitable take-up device having a sufficient capacity to accommodate such an amount of fencing as is normally produced by the weaving mechanism during the interval of an ordinary operation of removing the reeled fencing and commencing a new reeling operation. In the particular construction illustrated this take-up device comprises a take up roller or the like 17, preferably sufficiently large in diameter to avoid sharp kinks in the fence. This roller is carried upon a shaft 18, the ends of said shaft working within vertical slots 19 in a pair of end vertical posts 20 and 21. For this purpose the ends of the shaft 18 are mounted in journal blocks 22 and 23, said journal blocks working in the slots 19 by which they are guided. These journal blocks 22 and 23 are also supported by cables or ropes 24 and 25, which pass over pulleys 26 at the top ends of the posts. Counter weights 27 are also provided, which are of sufficient mass to raise the take up roller 17 with the necessary force to take up the slack fencing as fast as it is produced. In other words, the counterweights are of sufficient mass to draw off the newly woven fencing, and this is done by the raising of the take up roller 17.

There is in this way produced a reservoir for the storage of newly woven fence. The amount of fencing which may thus be accommodated is substantially equal to twice the amount of permissible vertical movement of the take up roller 17. For example, with posts allowing a sixteen foot vertical movement there may be taken up thirty-two feet of fencing in the storage reservoir without any corresponding rotation of the reeling mechanism.

The machine illustrated in Fig. 1 is of the intermittent type, that is, the type in which the actual forward advancement of the fencing is intermittent between the operations of placing successive slats. In this particular machine the fencing passes first over a guide roller 28, and then to the slack take-up mechanism just described.

After the fencing leaves the take-up mechanism it passes between a pair of sprocket drums or the like 29 and 30. These are journaled in suitable stands 31 and 32; and the two sprocket drums are also provided with ratchet wheels 33 and 34, which are engaged by pawls 35 and 36, respectively. These pawl and ratchet devices allow the fencing to be advanced in the direction of the arrow of Fig. 2 and towards the reeling mechanism, but when the reeling mechanism is stopped, the

sprockets and pawl and ratchet devices will prevent any backward movement of the fencing. This is important because the natural tendency of the take-up roller 17 is to draw the fencing backwards with a force equal to that tending to draw the newly woven fence forward. The reeling mechanism is driven by a chain 37. The driving end of this chain passes over a sprocket 38 (see Fig. 5) mounted upon a stub shaft 39. This stub shaft is driven from another shaft 40 through the medium of a friction clutch 41. The frictional force exerted in this clutch may be regulated by a counterweight 42 mounted upon a bell-crank arm 43 pivoted at 44, and in accordance with well understood principles. The shaft 40 is driven at a substantially constant speed, and the slip clutch allows the reeling mechanism to rotate at a variable speed, depending upon the size of the roll of fencing.

It will be understood that the normal or average reeling rate is substantially equal to the average rate of fence weaving. The actual rate of reel drive is, however, substantially greater than the average during the interval that the reel is being rotated. This is because after a fresh reel has been started it must be rotated fast enough to not only take up the fencing as it is produced, but also to absorb the extra amount of fencing produced during the interval of idleness of the reeling mechanism, so that before the new roll of fencing is completed the take-up roller 17 will have been drawn clear down to its lowermost position. Thereafter when the roll of fencing is being changed, the sprockets 29 and 30 will hold the fencing against any backward movement and the take-up roller 17 will rise, and thus take up the newly produced fence while the roller is being changed.

In the arrangement shown in Fig. 4, the actual pulling out of the fencing is accomplished by means of a large drum 45 having sprocket teeth 46. The fencing is then delivered from this drum to the take-up roller 17 in the manner already explained in detail. When using the type of construction illustrated in Fig. 4, the reeling mechanism is relieved of the work of pulling out the fencing from the weaving mechanism, since this work is performed by the drum 45. This type of construction is also preferably in that class of machines known as continuous feed as distinguished from intermittent feed machines.

While I have herein shown and described only certain embodiments of the features of my present invention, still I do not intend to limit myself thereto except as I may do so in the claims.

I claim:

1. In a machine for the production of fencing having longitudinal strand wires and transverse slats, the combination of means for weaving said fencing, a reeling device in-

cluding end hubs and a pair of removable bars extending between said hubs and adapted to receive the end portion of the fencing between them, means for driving one of said hubs, including means permitting a variable speed of rotation thereof, a guide roller over which the fencing passes after it is woven and having a fixed axial position, a pair of sprocket drums between which the fencing 5 subsequently passes in advance of the reeling mechanism, pawl and ratchet mechanism in conjunction with said sprocket drums permitting advancement of the fencing from the sprocket drums to the reeling mechanism 10 15 preventing backward movement of the fencing away from the reeling mechanism, a take-up roller intermediate between the guide roller and the sprocket drums aforesaid and overwhich the fencing passes in its travel 20 from the guide roller to the sprocket drums, guide means for said take-up roller permitting shifting of said take-up roller at right angles to its axis of rotation, and counterweights normally tending to draw said take-up roller away from the guide roller and sprocket drums to thereby create a lengthening loop of fencing, substantially as described.

2. In a machine for the production of fencing having longitudinal strand wires and transverse slats, the combination of means for weaving said fencing, removable reeling means for reeling the completed fencing, means for driving said reeling means at a 30 35 variable speed as permitted by the delivery of the fencing thereto, a guide roller over which the completed fencing passes, another element over which the fencing subsequently passes, means for preventing a retrograde movement of the fencing at the position of the last-mentioned element, a take-up roller at a position intermediate between said guide roller and said element, means permitting movement of the take-up roller in a direction 40 45 at right angles to its axis, to thereby establish a variable size loop of fencing intermediate between the guide roller and the element aforesaid, together with means tending to draw the take-up roller away from the 50 55 guide roller and said element for the purpose of extending the size of said loop, whereby when the rate of fence weaving exceeds the rate of reeling the excess fencing is taken up by the loop roller in the form of a loop, and whereby when the rate of reeling exceeds the rate of fence weaving the excess fencing stored in the loop is delivered to the reel, substantially as described.

3. In a machine for the production of fencing having longitudinal strand wires and transverse slats, the combination of means for weaving said fencing, means for reeling the woven fencing, a sprocket drum in advance of the reeling mechanism adapted to engage 60 65 the transverse slats, means for preventing

backward movement of said sprocket drum and thereby preventing backward movement of the completed fencing, together with a guide roller and a rotatable element in advance of the sprocket mechanism and over both of which members the fencing passes in its travel, a loop roller intermediate between said guide roller and said rotatable element and over which the fencing passes in its travel between the guide roller and the rotatable 70 75 element, and means for shifting the loop roller in a direction at right angles to its axis to thereby take up or give out fencing from a loop intermediate between the guide roller and rotatable element depending upon the 80 relative rates of operation of the weaving and reeling mechanism, substantially as described.

4. In a machine for the production of fencing having longitudinal strand wires and transverse elements, the combination of means for weaving said fencing, means for reeling the woven fencing, means for establishing a loop of fencing intermediate between the weaving and reeling mechanisms, means permitting variation in the size of said loop while retaining the fencing under tension therein, and means for preventing backward movement of the fencing intermediate between the loop and the reeling mechanism, substantially 90 95 as described.

5. In a machine for the production of fencing having longitudinal strand wires and transverse elements, the combination of means for weaving the fencing, means for reeling the woven fencing, and means intermediate between the weaving and reeling mechanisms operable to receive and store up or give out fencing during its travel between the weaving and reeling mechanisms and in accordance 100 105 with excess of rate of weaving or rate of reeling, substantially as described.

6. In a machine for the production of fencing having longitudinal strand wires and transverse elements, the combination of means for weaving fencing at a substantially uniform rate per hour, means for reeling the fencing at an intermittent rate, and means intermediate between the weaving and reeling mechanisms for establishing a loop of variable 110 115 size and adapted to either take up or give out fencing depending upon excess of rate of weaving or momentary rate of reeling, substantially as described.

7. In a machine for the production of fencing having longitudinal strand wires and transverse elements, the combination of means for weaving the fencing at a substantially uniform rate per hour, means for reeling the fencing at a variable rate varying between rates greater and less than the rate of weaving, and means intermediate between the weaving and reeling mechanisms operable to establish a loop of variable size to thereby take up fencing during intervals of 120 125 130

relatively slow reeling and give out fencing during intervals of relatively fast reeling, substantially as described.

8. In a machine for the production of fencing including longitudinal strand wires and transverse elements, the combination of means for weaving said fencing at a substantially uniform rate per hour, means for reeling the fencing at a variable rate including rates

10 greater and less than the rate of weaving,

driving means for said reeling means permitting slippage of the reeling means as compared to the rate of driving, together with means for establishing a loop of fencing intermediate between the weaving means and the 15 reeling means, and means permitting said loop to vary in size according to excess in rate of weaving or rate of reeling, substantially as described.

FOLGER ADAM.
